UNITED STATES PATENT OFFICE

ALBERT AURILLI, OF LAKE WORTH, FLORIDA

DESIGN FOR A RADIOCABINET

Application filed December 26, 1930. Serial No. 38,119. Term of patent 3½ years.

To all whom it may concern:

Be it known that I, ALBERT AURILLI, a citizen of the United States, residing at Lake Worth, in the county of Palm Beach and State of Florida, have invented a new, original, and ornamental Design for a Radiocabinet, of which the following is a specification, reference being had to the accompanying drawings, forming part thereof.

Fig. 1 is a front elevational view of the radio cabinet showing my new design, and Fig. 2 is a top plan view thereof.

I claim:

The ornamental design for a radio cabinet, as shown.

ALBERT AURILLI.
